UNITED STATES PATENT OFFICE.

JOHN HENRY HOFFMAN, OF WEST BRIGHTON, NEW YORK, ASSIGNOR TO POWER SPECIALTY COMPANY, OF NEW YORK, N. Y., A CORPORATION OF NEW YORK.

HANDHOLE PLUG.

Application filed September 21, 1923. Serial No. 662,945.

To all whom it may concern:

Be it known that I, JOHN HENRY HOFFMAN, a citizen of the United States, and resident of West Brighton, borough of Richmond, in the State of New York, have invented certain new and useful Improvements in Handhole Plugs, of which the following is a specification.

The general object of my present invention is to provide a simple and relatively inexpensive hand hole closure construction comprising a bushing securely mounted in the hole in the wall of the chamber to which the closure pertains, and adapted to be expanded into snug contact with said wall by the action of the fluid pressure in said chamber against the larger inner end of a tapered plug having its smaller end inserted in said bushing from the inner side of the latter, the larger end of the plug being too large to pass through the bushing. The invention insures the same strength and security against rupture and leakage in apparatus for high pressure work, as is obtained with the use of such a tapered plug when the latter is inserted in the inner end of an opening in the chamber wall proper, too small to pass the base of the plug, and at the same time permits the insertion and removal of the plug through the hole for which it forms a removable closure.

The various features of novelty which characterize my invention are pointed out with particularity in the claims annexed to and forming a part of this specification; for a better understanding of the invention however, its advantages and specific objects attained with its use, reference should be had to the accompanying drawings and descriptive matter in which I have illustrated preferred embodiments of my invention.

Of the drawings:

Fig. 1 is an elevation.

Fig. 2 is a section of the line 2—2 of Fig. 1; and

Figs. 3 and 4 are views taken similar to Fig. 2, each illustrating a different form of construction.

In the drawings, and referring first to the construction shown in Figs. 1 and 2, A represents a metal plate forming a portion of the wall of a boiler shell, a header or other chamber for fluid under pressure. In the wall A is formed a cylindrical hand hole opening A', which is internally threaded,

and receives an externally threaded bushing B, which is screwed into the opening A' from the outer side of the chamber of which the plate A forms a wall portion. Advantageously, as shown, the bushing B is provided with an external flange B' which abuts against the outer surface of the plate A in the assembled apparatus. The passage-way through the bushing B is normally closed by a tapered plug C, the base of which is small enough in diameter to pass through the hole A' before the bushing B is put in place, but is too large to pass through the bushing. The inner wall B² of the bushing is advantageously tapered as shown to correspond to the taper of the plug C. For security against accidental displacement, and to draw the parts snugly together on the initial closure of the hand hole, the plug C is advantageously provided at its outer end with an externally threaded extension C' of reduced diameter, which receives a nut E bearing against a washer D interposed between the inner end of the nut and the outer end of the bushing B.

With the described construction, it is obviously a simple matter to put the bushing B and hand hole plug C in place in the first instance, and thereafter to open the passage-way through the bushing, when this is necessary or desirable, by unscrewing the nut E and forcing the plug C inward, and to replace the plug and again close the passage-way through the bushing. The fluid pressure acting against the inner end of the plug C and tending to force the latter outward, tightens the joint between the plug and the bushing, and also tightens the threaded joint between the bushing and the plate opening A', particularly when, as is ordinarily preferable, the bushing B is made of a suitable ductile material such as copper or mild steel. In such case the deformation of the bushing, when used in apparatus subjected to heavy internal pressure, may make it necessary to cut the bushing out of the opening A', if it becomes necessary to remove the bushing, but this is a comparatively simple and inexpensive operation, and when performed the destroyed bushing may be replaced by a new one without injury to the plate A or to the hand hole plug C.

It will be obvious to those skilled in the art that various changes may be made in

the form of construction illustrated in Figs. 1 and 2. For example, as shown in Fig. 3, a single element BB may replace and perform the function of the bushing B and washer D of Figs. 1 and 2. Also as shown in Fig. 4 the washer member D of Figs. 1 and 2 may be replaced by a bushing member DD provided with a cylindrical flange portion D' at its inner side which abuts against the plate A and encircles the outer end of the bushing B, protecting the latter against accidental injury from external blows or forces.

Having now described my invention, what I claim as new and desire to obtain by Letters Patent, is:

1. The combination with a metallic chamber wall formed with an opening of a rigid metallic bushing member insertable into said opening from its outer end and firmly secured therein, and a tapered metallic hand hole plug entering the inner end of the passage through said bushing and prevented by its taper from passing axially through the latter but of a maximum external diameter small enough to pass through said opening.

2. The combination with a metallic chamber wall formed with a threaded opening of an externally threaded bushing of ductile metal screwed into said opening and a tapered metallic hand hole plug entering the inner end of the passage through said bushing and prevented by its taper from passing axially through the latter but small enough in maximum external diameter to pass through said opening.

3. The combination with a metallic chamber wall formed with a threaded opening of an externally threaded bushing of ductile metal screwed into said opening, and pro-

vided with an outwardly projecting flange bearing against the outer side of said wall at the margin of said hole, and a tapered metallic hand hole plug entering the inner end of the passage through the latter but small enough in maximum external diameter to pass through said opening.

4. The combination with a metallic chamber wall formed with an opening of a rigid metallic bushing threaded into said opening from the outer side of said chamber, a tapered hand hole plug inserted into said bushing from the inner end of the latter and prevented by its taper from passing axially through the latter but of small enough maximum diameter to pass through said opening, said plug having a threaded outer end, a nut thereon and a cup shaped washer surrounding said threaded end portion of the plug and the outer end of the bushing and interposed between said nut and the chamber wall.

5. The combination with a metallic chamber wall formed with a threaded opening of an externally threaded bushing of ductile metal screwed into said opening, and provided with an outwardly projecting flange bearing against the outer side of said wall at the margin of said hole, and a tapered hand hole plug entering the inner end of the passage through the latter but small enough in maximum external diameter to pass through said opening, said plug having a threaded outer end, a nut thereon, and a washer surrounding said threaded portion and interposed between said nut and the outer end of the bushing.

Signed at New York in the county of New York and State of New York this 18th day of September A. D. 1923.

JOHN HENRY HOFFMAN.
